Primary Examiner — Jonathan J Han

(57) CLAIM

We claim the ornamental design for a shoe, as shown and described.

DESCRIPTION

FIG. 1 is a perspective view of a shoe showing the new design.

FIG. 2 is a lateral side view thereof.

FIG. 3 is a medial side view thereof.

FIG. 4 is a top view thereof.

FIG. 5 is a front view thereof; and,

FIG. 6 is a back view thereof.

The broken lines are used to illustrate portions of the shoe that form no part of the claimed design.

1 Claim, 5 Drawing Sheets
